SMOKING PIPE

Edward M. Yamamoto, Spokane, Wash.

Application August 22, 1945, Serial No. 612,111

4 Claims. (Cl. 131—218)

1

The present invention relates to certain new and useful improvements in a smoking pipe and is particularly directed to providing in the shank of the pipe, a number of parallel channels, interconnected in series, so as to provide a greatly elongated smoke passage extending back and forth in a zigzag fashion from the pipe bowl to the bit end.

This improved structure materially reduces the heat of the smoke and affords greater comfort in smoking. It is well known that vigorous smoking will sometimes heat up the pipe to an uncomfortable condition so that the smoke is hot enough to burn the smoker's tongue. The present invention obviates that inaptitude by greatly elongating the length of the smoke passage without increasing the length of the pipe as a whole. The invention affords the benefit of an extremely long stem pipe without resorting to any increased length of the pipe.

The accompanying drawing shows an example of the physical embodiment of my invention.

Fig. 1 shows an elevation of the invention.

Fig. 2 shows a vertical longitudinal section of Fig. 1.

Fig. 3 shows a vertical longitudinal section of the shank portion of the pipe, separately.

Fig. 4 is a vertical transverse section of the shank taken on the line 4—4 of Fig. 3.

Fig. 5 is a vertical transverse section of the shank taken on the line 5—5 of Fig. 3.

The pipe comprises a shank portion S having a boss 12 upon which the bowl 15 is mounted by means of a hollow adapter screw 14 which is recessed into the bottom of the pipe bowl as shown.

This shank portion S embodies a tubular outer wall 11 and a tubular inner wall 10. This inner wall is spaced from the outer wall by four longitudinal wings 6, 7, 8 and 9, which form partitions dividing the shank S into four longitudinal channels A, B, C and D which surround the central channel E within the inner wall 10. These five channels have their ends connected in series so as to form one continuous smoke passage five times the length of the shank S.

The bowl end of the shank S is closed by a threaded cap 16 and a suitable gasket 17 closing the ends of all of said channels. The opposite end of the shank has a nipple 18 threaded thereon and is provided with a centrally perforated gasket 19 closing the ends of all of said channels except the central channel E. The bit 20 is fitted into the nipple 18, and communicates with the central channel E.

The upper channel A communicates with the

2

bowl 15 through the bore 1 in the screw 14. The opposite end of this channel A communicates with the channel B through the passage 2 in the partition 6. Thus the channels A and B are connected together at the bit end or near end. At the bowl end which may properly be called the far end, the partition 7 is cut away to form the passage 3 which connects the far ends of the channels B and C. The near end of the partition 8 is cut away to form the passage 4 which connects the near ends of the channels C and D. The far end of the inner wall 10 is cut away to form the passage 5 which connects the far end of the channel D with the central channel E. The bit 20 opens into the near end of the central channel E.

It will be seen that smoke enters through the opening 1 and passes forwards through the channel A, then through the passage 2 and backwards through the channel B, then through the passage 3 and forwards through the channel C, then through the passage 4 and backwards through the channel D, then through the passage 5 and forwards through the channel E and into the bit 20.

In this manner the smoke travels back and forth in a zigzag path five times as long as the shank of the pipe.

It will be seen that the invention provides a greatly elongated smoke passage and assures a cool smoke. It will also be seen that the several smoke channels can be readily cleaned by removing the screw threaded nipple 18 and cap 16.

The five smoke channels have been shown by way of example, and the invention can equally well employ seven or nine smoke passages, as for instance if the illustrated channels A, B, C and D are made as round bores then there will be room for four other round bores between them, making nine channels in all, and these can be connected in series so as to form a continuous passage.

Various modifications may be resorted to without departing from the invention as defined in the following claims.

45 I claim as my invention:

1. A smoking pipe comprising a shank portion having an outer wall and an inner wall, said inner wall forming a central tubular channel in said shank, longitudinally extending wings forming partitions between said inner and outer walls and dividing the space into four channels surrounding said central channel, a pipe bowl mounted upon said shank, a closure for the bowl end of said shank, a nipple threaded onto the opposite end of said shank and closing said

four channels, and a bit engaged in said nipple and communicating with said central channel, said bowl communicating with one of said four channels, the bit end of that channel communicating with a second channel, the bowl end of said second channel communicating with a third channel, the bit end of said third channel communicating with a fourth channel, and the bowl end of said fourth channel communicating with said central channel, to thereby form a continuous zigzag passage back and forth between said pipe bowl and said bit.

2. A smoking pipe comprising a shank portion having a central channel and an even number of surrounding channels all extending parallel from end to end of said shank, a nipple threaded upon said shank and closing all but said central channel, a bit fitted into said nipple and communicating with said central channel, a closure threaded onto the far end of said shank and closing the far end of all of said channels, and a pipe bowl secured to said shank and communicating with the far end of one of said channels, all of said channels being connected in series and forming a continuous passage from said pipe bowl to said bit.

3. A smoking pipe comprising a shank portion having an outer wall and an inner wall, said inner wall forming a central tubular channel in said shank, longitudinally extending wings forming partitions between said inner and outer walls and dividing the space into four outer channels surrounding said central channel, a nipple threaded onto one end of said shank and closing all but said central channel, a centrally perforated gasket interposed between said nipple and said shank, a bit fitted into said nipple and communicating with said central channel, a closure threaded onto the far end of said shank and closing the far end of all of said channels, a gasket interposed between said closure and said shank, and a pipe bowl mounted upon said

shank and communicating with the far end of one of said outer channels, all of said outer channels being connected together in series between said pipe bowl and the far end of said central channel to form a continuous zigzag passage back and forth between said bit and said pipe bowl.

4. A smoking pipe comprising a shank portion having a central channel and an even number of parallel channels extending from end to end of said shank, a nipple threaded onto one end of said shank and closing all but said central channel, a centrally perforated gasket interposed between said nipple and said shank, a bit fitted into said central channel, a closure threaded onto the far end of said shank and closing the far end of all of said channels, a gasket interposed between said closure and said shank, and a pipe bowl mounted upon said shank and communicating with the far end of one of said parallel channels, all of said parallel channels being connected together in series between said pipe bowl and the far end of said central channel to form a continuous zigzag passage back and forth between said bit and said pipe bowl.

EDWARD M. YAMAMOTO.
